The ornamental design for a column base metal fitting, as shown and described.

DESCRIPTION

FIG. 1 is a top plan view of column base metal fitting showing our new design;

FIG. 2 is a bottom plan view thereof;

FIG. 3 is a front elevation view thereof, the rear and both sides being identical;

FIG. 4 is a cross sectional view, taken in the direction of line 4-4 of FIG. 1;

FIG. 5 is a cross sectional view, taken in the direction of line 5-5 of FIG. 1;

FIG. 6 is a cross sectional view, taken in the direction of line 6-6 of FIG. 1; and,

FIG. 7 is a top perspective view of FIG. 1.
